[57] **CLAIM**

The ornamental design for a loran receiver, substantially as shown and described.

DESCRIPTION

FIG. 1 is a perspective view of a loran receiver showing my new design; and

FIG. 2 is a front elevational view of the loran receiver shown in FIG. 1.

The right side of the loran receiver is a mirror image of the side shown in FIG. 1. The rear surface of the receiver is a plane surface.
